DAVID S. HULFISH, OF TORONTO, ONTARIO, CANADA, ASSIGNOR, BY MESNE ASSIGNMENTS, TO GENERAL ENGINEERING AND CONSTRUCTION COMPANY, LIMITED, OF TORONTO, CANADA, A CORPORATION OF ONTARIO.

PRINTING-TELEGRAPH ALPHABET.

1,118,650.

Specification of Letters Patent.

Patented Nov. 24, 1914.

Application filed April 20, 1911, Serial No. 622,177. Renewed April 9, 1914. Serial No. 830,797.

To all whom it may concern:

Be it known that I, DAVID S. HULFISH, a citizen of the United States of America, and a resident of Toronto, county of York, 5 Province of Ontario, and Dominion of Canada, have invented a new and useful Improvement in Printing-Telegraph Alphabets, of which the following is a specification.

10 My invention relates to an English alphabet, the characters of which are built up from predetermined combinations of impressions from four elemental component types, the impressions being potentially periodically 15 recurrent considered lineally along the line of writing.

My invention finds its chief application in automatic printing telegraph systems in which a plurality of component types are 20 electromagnetically controlled and operated by current impulses over line conductors, the selection being consummated by means of a perforated transmitting tape. Experience in the use of such systems has proven that a 25 higher transmission efficiency is attained by the use of an alternating current. Particularly is this true under adverse line conditions approaching the limits of commercial practicability. A resort to the use of alternating current imposes as a requirement for 30 high speed transmission that a maximum number of the alternations in a current of a definite frequency shall be utilized to imprint predetermined types in order that the 35 maximum imprinting possibilities of a current of a definite frequency may be realized. It is with a view toward providing a directly readable English alphabet the characters of which are imprinted from impressions 40 of component types available for selection only in cyclic order, that my invention is directed. I accomplish this and other desirable features by utilizing a design of character that is built up from a number of 45 predetermined impressions from component type faces, the predetermined impressions being selected from a potentially periodically recurrent series of impressions from all 50 of the four component types.

50 In the figures which accompany and form a part of this specification and in which like numerals designate corresponding parts throughout; Figure 1 is a plan view of the four component type faces arranged in the

form of a printing telegraph printing symbol. Fig. 2 is a view of a record of the impressions of all of the type faces such as would result from utilizing all of the alternations of an alternating current for imprinting purposes. Fig. 3 is a view of my 60 improved alphabet together with the numerals from 0 to 9 so spaced with regard to Fig. 2 as to illustrate the principle of its design.

As there are numerous methods known in 65 the printing telegraph art for selectively operating types having faces as shown in Fig. 1, it is not deemed necessary in this disclosure to illustrate any definite arrangement of apparatus or circuits for their operation. 70 Assuming therefore, that the type faces as shown in Fig. 1 are maintained in such relation to a recording surface that each may record an impression thereon, that the recording surface be moved under the type 75 as viewed in Fig. 1 from right to left at a speed which is commensurate with the alternations of the alternating currents used, and that the distance between any two maximum current values is further commensurate 80 with the spacing between the types as indicated by the perpendicular lines in Fig. 1, and assuming further that type face 4 is operated by a positive potential, then from the foregoing it follows that type face 3 is 85 operated by the next succeeding negative impulse, type face 2 is operated by the next succeeding positive impulse while type face 1 is operated by the next succeeding negative impulse. Therefore, if an alternating 90 current of a predetermined frequency be placed through the controlling magnets of the pens 4, 3, 2, 1, they will be imprinted in cyclic distribution on the receiving tape and the resultant record will be a continuous 95 lattice as shown in Fig. 2. If now a transmitting tape be perforated with a predetermined spacing of perforations, it will be noted that it will be possible to select from the operating alternating current, impulses 100 of predetermined potential to operate predetermined type faces to imprint their impressions in proper relation to previous imprints, in the course of their potential recurrence.

105 The letter "A" is built up and recorded by the use of an alternating current as follows: The first positive current maximum

imprints pen 4, the record tape moves after such imprint from right to left a distance equal to that between any two type faces or one tape interval while the current changes 5 in value from positive maximum to negative maximum at which time pen face 3 is in a potential condition of operation but through the predetermined spacing of the perforations in the transmitting tape the impulse 10 for its operation is omitted and the pen is not recorded; the tape continues and moves one tape interval while the current changes from negative maximum to positive maximum and pen face 2 is imprinted with its 15 median point over the median point of the previous imprint of pen face 4; the record tape again moves one tape interval while the current changes from positive maximum to negative maximum, placing pen face 1 20 in a potential condition of operation but its imprint is omitted as before stated through the predetermined spacing of the perforations in the transmitting tape; the record tape again moves one tape interval while 25 the current changes from negative maximum to positive maximum and pen face 4 is again imprinted a distance away from the previous imprint of pen face 4 of four tape intervals or the width of a complete normal 30 character such as "A"; the tape again moves one tape interval while the current changes again in value from positive maximum to negative maximum placing pen face 3 again in a potential condition of operation; the 35 record tape now moves another tape interval while the current changes from negative maximum to positive maximum at which time pen face 2 is again imprinted with one of its extremities abutting one of the 40 extremities of the previous imprint of pen face 2 and its median point over the median point of the last imprint of pen face 4; the record tape moves again one tape interval while the current changes from positive 45 maximum to negative maximum at which time pen face 1 is imprinted with its vertical leg registering with the upper half of the first imprint of pen face 4 and with the extremity of its horizontal leg abutting the 50 last imprint of pen face 4 to form the letter

"A". Thus any of the letters of the alphabet and the numerals as illustrated in Fig. 3, may be imprinted by any transmitting tape which is provided with groupings of perforations which select from the potentially cyclic recurrent impressions, a predetermined group of impressions. 55

It will be observed that with my improved design of alphabetical characters, I attain, through the regularity of the operating impulses, a cyclic distribution of the impressions which permits the use of an alternating current for transmission; from the particular design of character, a pleasing and extremely legible alphabet, and further, a minimum length of receiving tape for a given message. I thus realize a combination of desirable features which has heretofore been striven for with but meager success. 70

Having thus described my invention, what I claim as new and desire to secure by United States Letters Patent is as follows:

1. An English alphabet for printing telegraph systems, the characters of which comprise vertical impressions, and top, median and bottom horizontal impressions, the median horizontal impressions when appearing in contact with the vertical impressions always appearing with a median point 75 over a median point of the vertical impression. 80

2. An English alphabet for printing telegraph systems the characters of which comprise vertical impressions and upper, lower 85 and median horizontal impressions, said upper and lower horizontal impressions registering at one end with a vertical impression when meeting said vertical impression and the median horizontal impressions always crossing a vertical impression when meeting a vertical impression. 90

Signed by me at Toronto, county of York, and Province of Ontario, in the presence of two witnesses.

DAVID S. HULFISH.
